(No Model.)

D. L. ADAMS.

SECTIONAL STEAM BOILER.

No. 268,592.

Patented Dec. 5, 1882.

UNITED STATES PATENT OFFICE.

DANIEL L. ADAMS, OF POTTSVILLE, PENNSYLVANIA.

SECTIONAL STEAM-BOILER.

SPECIFICATION forming part of Letters Patent No. 268,592, dated December 5, 1882.

Application filed May 15, 1882. (No model.)

To all whom it may concern:

Be it known that I, DANIEL L. ADAMS, a citizen of the United States, residing at Pottsville, in the county of Schuylkill and State of Pennsylvania, have invented certain new and useful Improvements in Sectional Steam-Boilers; and I do declare the following to be a full, clear, and exact description of the invention, such as will enable others skilled in the art to 50 which it appertains to make and use the same, reference being had to the accompanying drawings, and to the letters and figures of reference marked thereon, which form a part of this specification.

15 Figure 1 is a vertical elevation of my improved steam heating-furnace, a portion of one wall being removed for the purpose of showing its internal construction. Fig. 2 is a horizontal section on line xx of Fig. 1, and Fig. 3 represents detail views of the sectional grate.

Like letters of reference are used to designate the same parts in the several views.

A denotes the furnace-walls. B is the grate, C is the fire-door, and D is a door that communicates with the ash-pit.

25 The boiler is constructed in sections on the most simple and most effectual plan for quick generation of steam. It consists of a series of horizontal pipes, E, forming the top of the boiler or steam generator, a series of inclined pipes, F, communicating with the horizontal pipes, and a series of double inclined tubes, G, provided with elbows and arranged to communicate with the large pipes E and F. The 30 tubes G, connecting the pipes E and F, are arranged in pairs, as shown in Fig. 2, and may be of any desired number, according to the size of the furnace. The pipes E F are preferably composed of cast-iron, while the tubes G are

35 made of wrought-iron. The pipes F are flanged at their lower ends, and are bolted to flanged elbows or branches that are formed on a mud-drum, H, which is arranged transversely in the lower part of the furnace behind the bridge-wall I, as shown in Figs. 1 and 2. The upper ends of the pipes F are also flanged for connection with flanged branches formed on the horizontal pipes E, as shown in Fig. 1. The pipes E F and connecting-tubes G are arranged 40 across the furnace in such a way as to nearly fill the space above and to the rear of the grate, the contents of the pipes and tubes being thus

thoroughly exposed to the influence of the heated air.

It will be seen that the tubes G are inclined 55 back toward the rear pipes, F, and are elbowed into the upper pipes, E, at nearly a right angle, the inclination of the elbow being slightly forward. By this manner of arranging the pipes and tubes a positive circulation is secured, and 60 all sediment is permitted to drop freely into the mud-drum through the rear pipes, F.

At the top of the furnace and communicating with the rear ends of the horizontal pipes E is a steam-drum, K, which is also made in 65 sections, that are suitably flanged and bolted together, so that the length of the drum may be readily made to correspond with the width of the furnace and with the number of horizontal pipes employed in the construction of 70 the steam-generator.

The sectional grate B is composed of the independent or separate bars a, which are T-shaped in cross-section. These grate-bars are provided at each end with pins or projections 75 b b, by means of which they are pivoted in bearings c c at the front and back.

At the front end of each grate-bar is a downward extension having a pin, d, that connects with a sliding bar or link, e, to which each 80 grate-bar is thus connected. This link has a pin, f, which is connected by a yoke, g, with a rod, h, to which is attached a lever, i, whereby all the bars may be shaken or rocked at once, thus grinding up the cinders and shaking out 85 the dust and ashes. The upper surfaces of the grate-bars a are formed with interlocking lugs or projections, as shown in Fig. 2, thus forming a nearly-solid grate-surface without interfering with the draft, the lugs or projections 90 also serving to break or grind the cinders when the bars are moved or rocked.

It will be seen that any of these grate-bars when worn or broken can be readily removed and replaced without interfering with the 95 others. At the front and sides of the furnace are doors or openings k k, by which access is had for the purpose of cleaning the pipes and tubes. The fire-door and ash-door are provided with automatic catches m to hold them open 100 while feeding the fire or removing ashes.

The construction of the furnace is such, the wrought-iron tubes G being directly over the fire, that the heat ascends between and around

the said tubes, rises to the upper or horizontal pipes, E, which are set close together and covered above with a layer of bricks and mortar, is then deflected twice toward the lower ends 5 of the rear pipes, F, and, passing through a narrow space above the mud-drum, finally escapes to the flue L through the space at the back of the rear inclined pipes. It will be seen that the tubes and pipes are so arranged as to pre-
clude any possibility of the heat escaping except in the manner described. The bridge-
wall I, being near the center of the lower tubes and in the rear of the fire-place and grate, as-
ists in guiding the heat over the entire heat-
ing-surface of the steam-generating pipes. The
water contained in the pipes E F and tubes G
is thus fully exposed to the heat of the furnace,
and steam is rapidly generated and passed to
the drum K, whence it may be conducted to
any desired points. The boiler is fed from
below through a pipe, M, that enters at one
end of the mud-drum H, and a water-line is
preferably maintained at about the center of
the horizontal pipes E, the upper portions of
which form a steam-space.

It will be seen that the inclined position of
the pipes F and tubes G is such that while the
circulation is rapidly maintained the sediment

is caused to gravitate into the mud-drum with-
out interruption or binderance. This construc-
tion also obviates the disagreeable rattling and
clanging incident to many steam-heaters.

While all the parts of the apparatus are
formed in detachable sections, there will be no
difficulty in adjusting the capacity of the heater
according to the requirements of the situation
in which it is to be placed.

Having thus described my invention, what I
claim as new, and desire to secure by Letters
Patent, is—

A steam heating apparatus consisting of a
sectional boiler composed of the upper hori-
zontal pipes, E E, rear inclined pipes, F F, and
double inclined connecting tubes G G, the
mud-drum H, communicating with the lower
ends of the pipes F, the feed-pipe M, entering
the mud-drum, and the sectional steam-drum
K, connecting with the upper horizontal boiler-
pipes, all constructed and combined as and for
the purpose described.

In testimony whereof I affix my signature in
presence of two witnesses.

DANIEL L. ADAMS.
